WELL HEAD EQUIPMENT

James H. Howard, Houston, Tex., assignor to
J. M. McEvoy & Company, a corporation

Application December 16, 1931, Serial No. 581,301

16 Claims. (Cl. 166—15)

The invention relates to an improvement in well head assemblies arranged to control the flow of fluid from the well, as well as manipulation of the tubing therein.

5 It is one of the objects of the invention to provide an assembly for closing the well and supporting the tubing as well as preventing any leakage by the tubing while it is being inserted and withdrawn from the well.

10 Another object of the invention is to provide an improved tubing hanger which may be readily inserted and withdrawn from the well casing.

Another object of the invention is to provide an improved seal about the tubing while it is 15 being run into or withdrawn from the well.

Another object of the invention is to provide a seal for well heads wherein any liquid passing into the sealing assembly can be withdrawn to avoid the accumulation of hydraulic forces within 20 the sealing assembly.

Another object of the invention is to provide a frangible closing member for the tubing while it is being run into the well.

A still further object of the invention is to 25 provide a tubing hanger which is slidable upon a section of tubing and adapted to receive one of the tubing couplings in order to support the string of tubing.

A still further object of the invention is to 30 provide a tubing hanger adapted to seat upon retractable dogs in the well casing.

It is also an object to provide a tubing hanger which may be withdrawn with the tubing by being lifted by the tubing coupling next below the 35 section of tubing on which the hanger is slidable.

Other and further objects of the invention will be readily apparent when the following description is considered in connection with the accompanying drawings, wherein

40 Figure 1 is a central vertical section of the upper end of a well head equipment showing a sealing assembly.

Figure 2 is a continuation of Figure 1 and showing the retractable dogs for supporting the 45 string of tubing in combination with a closure valve and the tubing in the well casing.

Figures 3 and 4 are sections taken on the lines 3—3 and 4—4, respectively, of Figures 1 and 2.

Figure 5 shows the tubing hanger seated and 50 supporting the tubing.

Figure 6 is a side elevation partly in section showing a modified form of sealing assembly which may also be used as a tubing hanger.

Figure 7 is a broken detail sectional view of a 55 form of pressure head insert to be used in lieu of the slips in the bowl of the casing head.

The invention is best seen in section in Figures 1 and 2 and embodies the usual casing 2, which is anchored in the earth in the usual manner. This casing serves as a support or founda- 60

tion for the well head equipment and is cemented in position to withstand the fluid pressure created in the well. Connected to the casing 2 is a tubing hanger support or connection 3, which is of special construction and embodies the flange 5 having formed thereon the projections 5. Each of these projections 5 is arranged to slidably receive a bolt 6, which may be manipulated by means of a nut 7. This bolt has mounted on the end thereof a dog or support block 8, which 10 projects beyond the inner circumference 9 of the coupling 3.

A cap 10 may or may not be provided to protect the end of the bolt 6 and the nut 7. If desired, a spring may be positioned between the 15 block 8 and the base of the recess in which the block is positioned in order to normally press the block inwardly in hanger-receiving position. It is to be understood that the detail construction given above may be altered to embody other 20 forms of control for the dogs or blocks.

Disposed above the coupling 3 is a gate valve 15, which may be connected to the coupling 3 by means of a nipple 16 or the coupling and gate valve housing may be flanged together. The 25 gate valve 15 is of usual construction and embodies the gate member 17, which is slidable transversely of the passage 18 from the casing 2. The gate 17, as is well understood, may be closed when there is no pipe or tubing in the well to 30 completely close the well.

A piece of pipe or swaged nipple 20 is shown as positioned above the gate valve and serves as a support for the sealing assembly seen in Fig. 1 and indicated generally at 22. This sealing assembly is arranged to maintain a seal about the string of tubing 23 while it is being run into or withdrawn from the well or while it is positioned in the well.

The lower end of the tubing is indicated at 40 24 in Fig. 2 and is representative of any section of tubing which may carry a screen or liner or other construction which is to be positioned in the well.

The coupling 25 is representative of standard 45 couplings and is arranged to receive a frangible disc 26, which may be made of glass or other suitable material. This disc is preferably positioned between the two adjacent sections of tubing which are connected by the coupling 25 and it 50 is intended that after the tubing has been properly positioned in the well that some object such as a small nipple may be dropped into the tubing to break the disc 26 and permit a flow of liquid into the tubing. This construction is of particular advantage in that no blowout can occur through the tubing while the tubing is being run into the well, because the tubing is closed by this disc 26. For purposes of illustration, a similar 55 disc 26 has been shown between the two adjacent 60

sections of tubing in Fig. 1. It is contemplated that one or more of these discs 26 may be provided and that they may be positioned either at the bottom or the top of the string of tubing, or 5 at any intermediate position.

A coupling 30 is shown as connecting the sections 31 and 32 of tubing. These sections are preferably the sections of pipe which are adjacent the lowermost end of the tubing and the coupling 30 is not a standard coupling such as 25 but is preferably somewhat larger in diameter in order to support the tubing hanger or collar 33. When it is intended to run the tubing into the well the collar 33 is positioned on the section 32 10 and the coupling 30 is then attached to the lower end of the section 32 so that the collar 33 will rest upon the coupling 30. The coupling 30 is then attached to the section 31 and this assembly 15 is lowered into the pipe or nipple 20.

20 As soon as the coupling 30 and collar 33 have been lowered to a position such as seen in Fig. 1 the sealing assembly 22 may be passed over the pipe section 32 and attached to the pipe 20 by means of a coupling 35 or the assembly 22 may 25 have been passed onto the tubing 32 prior to the positioning of the collar 33. In any event the pipe section 32 is arranged to be passed through the sealing assembly 22 and to carry the collar 33. From the position of the parts shown in Figs. 1 30 and 2 the string of tubing 23 is lowered into the well after the gate 17 has been opened. When the collar 33 reaches the elevation of the blocks or dogs 8 carried by the casing it is supported on these blocks. It will be noted that the collar 33 35 is of greater diameter than the opening between the blocks 8, so that it will seat upon these blocks and the wings 36 on the side of the hanger tend to center the same at the time it seats upon the blocks or dogs 8, see Fig. 5.

40 The lowering of the tubing 23 is then continued and the opening 37 through the center of the hanger 33 is of such diameter that it will permit standard couplings such as 25 to pass down into the well. When sufficient length of tubing has 45 been lowered into the well, and it is desired to suspend the tubing from the collar or hanger 33, an enlarged coupling such as 35 may then be positioned as a connection on the uppermost end of the upper section of tubing. A nipple or other 50 piece of tubing is then connected to this coupling 35 and the lowering of the string is continued until such coupling seats in the hanger recess 40 in the collar 33.

This recess 40 has a seat 41 therein to receive 55 the enlarged coupling 35, and in this manner serves to support the entire string of tubing. After this coupling is seated in the recess 40 the nipple or setting tool 34 used to land the tubing may or may not be removed. If it is removed, the 60 well may be flowed directly through the casing. If it is retained in position the well may be flowed through the tubing and in this event the sealing assembly 22 serves to maintain a seal about the tubing.

65 When the tubing is to be withdrawn from the well the nipple or other piece of pipe connected to the coupling 35, which is positioned in the recess 40, is raised and the coupling 35 will be withdrawn from the recess. The tubing will be 70 withdrawn from the well until such time as the lower coupling 30 engages the base of the collar 33 whereupon it is raised from its position on the dogs 8 and withdrawn from the well with the tubing. In this manner a hanger for the tubing has 75 been positioned when the tubing was first started

into the well and is withdrawn when the tubing is removed from the well without further manipulation or operations on the part of the workers. The dogs 8 are adjustable radially to accommodate different sizes of tubing or different sizes of hanger and can be withdrawn so that they will not interfere with the passage of any equipment into or out of the well. The upper end of the collar 33 is tapered at the entrance to the seat 41 in order to assist the coupling 35 in entering the 10 recess 40.

The sealing assembly 22 may or may not be used in combination with the hanger or collar 33 and the frangible disc 26, but in order to obtain a complete seal of the well while the tubing is 15 being run this assembly may be positioned on the well head. The assembly includes a housing 45, which is arranged to receive a plurality of sealing elements 46, each of which includes a spacer or support ring 47 and the sealing ring 48. These 20 sealing rings are preferably positioned as shown in Fig. 1 with a downwardly extending flange 49 thereon engaging the tubing or pipe. This flange 49 provides an additional amount of material to increase the sealing area in contact with the 25 pipe and to also form an enlarged body of material which will not flow upwardly through the opening such as 50 in the support ring 47 when the packing ring is subjected to enormous pressures. 30

The opening 50 in the support rings is made of sufficient diameter to pass not only the standard coupling 25 but also the enlarged coupling 30. It should be noted that the support rings 47 and the sealing rings 48 are spaced apart to form a trap 35 51 in order to provide sufficient area for the rim or flange 49 to move downwardly when a coupling is passing downwardly into the well. The packing rings 48 have enlarged rims 52 which are positioned in corresponding recesses in the two 40 adjacent support rings 47.

The cutaway area 51 is in the nature of a trap which is defined by the concaved face 53 on the supporting ring 47 and by the concaved face 58 on the lower side of each of the sealing rings 48. 45

A particular feature of advantage in the sealing assembly 22 is the fact that some of the support rings 47 are provided with outlet openings such as 54, which lead to a pipe or bleeder line 55. It has been found by experience that when pressure occurs in the well there is an accumulation of such pressure in the trap 51 between the sealing rings. If this pressure is caused by a gas which tends to flow the rings 48 through the openings 50, this may bind the tubing; whereas, if this pressure can be led away from the area by the rings it assists materially in forming a proper seal. If the pressure is due to the presence of liquid which has leaked past the first one or two rings, it then forms a solid hydraulic piston between the adjacent sealing elements and any sealing effect then disappears. If, however, this fluid can be led away from the trap 51 as it accumulates, the sealing rings 48 may still remain in a flexible condition and serve their sealing 65 function without hindrance from the accumulating liquid. The bleeder line 55 is shown as controlled by a valve 56 and this valve may be opened to allow a constant flow of accumulated fluid or it may be closed and opened periodically to release the accumulated fluid, and in this manner 70 reduce the pressure in the sealing assembly.

Lock rings 57 at opposite ends of the housing 45 serve to position and assemble the sealing elements and supporting rings. 75

In order to anchor the tubing while it is being run in or withdrawn from the well a set of slips 60 have been positioned in the bowl 61, which is connected by a coupling 62 to the housing 45 of the sealing assembly. To insure that the tubing string will not be blown from the well due to the disc 26, a locking mechanism 63 has been provided in the head or bowl 61 in the form of a set of balls 65, which are normally held in contact with the tubing string 23 by means of the springs 66. These balls travel in a tapered groove or seat 67 so that they are urged against the pipe and form a rigid stop which will prevent upward movement of the tubing. When it is desired to raise the tubing from the well the slips 60 are removed and a nipple or other member may be seated in the bowl 61 to cause downward movement of the balls 65 to remove them from contact with the tubing.

While a specific form of sealing assembly 22 has been shown and described it is contemplated that such assembly may assume various forms without departing from the spirit of the invention, because broadly this sealing assembly contemplates the seal about the tubing while it is being run into the well and while the tubing is suspended in the casing.

In Figure 6 a modified form of oil saver or sealing assembly has been illustrated, which assembly is arranged upon the nipple or pipe 20, best seen in Figure 2. In this modification a coupling 70 has been provided with the flow lines 71 and 72 so that the fluid may be conducted away from the well.

Mounted above the coupling 70 is the sealing assembly 74, which comprises the base 75 and a cap 76. These two members are joined by a sleeve or housing 77, which is arranged to support the packing or sealing elements 78. These elements are preferably spaced annular rings or segments 79 of flexible material which are arranged to yield sufficiently to permit the passage of a coupling such as 30 or 35. These segments 79 are maintained in spaced relation by means of the spacer rings 80, which may be stacked within the sleeve 77 and firmly positioned by means of a locking ring 81. It is intended that these flexible wipers or packing rings are to engage against the tubing, or any couplings passing therethrough, with sufficient pressure to maintain a seal. It is probable that there will be some leakage by these wiping rings, but, with a view of extending the usefulness of the sealing assembly, a drain or bleed line 82 has been provided which serves somewhat the same purpose as the bleed line 55 of Figure 1. A valve 83 is provided on this line so that any fluid may drain off which may accumulate within the chamber 84 between the wiping rings. It seems obvious that if the fluid is drained off as it accumulates in the chamber 84 that the upper wiping rings 85 will always be in proper condition to maintain a seal with the tubing.

The coupling or cross 70 is of special construction and is provided with a tapered seat 86, which is arranged to receive the enlarged coupling 35, which may be lowered into the cross in order to support the tubing. When a cross such as 70 provided with the seat 86 is used, the tubing will then be hung at a position above the gate valve, or the gate valve may be dispensed with. It seems obvious that a cross may be provided at this position, which does not embody the seat 86, but is of sufficient size to permit the free passage of the enlarged coupling 35, and, when this arrange-

ment issued, the hanger or collar 33 will be included in the tubing assembly and will seat upon the block 8 as best seen in Figure 5.

The cap 76 is shown as being formed with a tapered bowl 80, which receives the slips 61. With this additional structure, it is possible to support the tubing at any desired elevation, irrespective of whether the tubing or hanger is properly seated or not and these slips will be used when the tubing is run into or withdrawn from the well.

Figure 7 shows a somewhat modified form 76' of the cap 76 in which the bowl 80' has been cut away as at 82, which recess is formed with ratchet or screw thread teeth 83. These teeth are arranged to receive a latching dog 84 carried by a pressure head or pressure insert 85. The dogs 84 are normally pressed outward against the teeth 83 by the springs 86 in a manner which is well understood and which is disclosed in an application for patent of Joseph H. McEvoy, Serial No. 361,059, filed May 7, 1929.

The insert 85 includes the upper plate 87, the lower plate 88 and the compressible packing ring 89. It is intended that this head 85 will be of two or more parts, preferably hinged together so that the insert may be dropped into the bowl 80' and will be latched in position by the automatic action of the dogs 84 engaging the teeth 83.

It is contemplated that this insert 85 may be used in lieu of the slips 60 shown in Figure 6 or the slips 60 shown in Figure 1. It is to be understood that when this pressure insert is to be used that a cap such as 76' will be positioned upon the sealing assembly instead of a cap having a uniformly tapered bowl. It will be readily apparent that with the insert 85 a complete and positive seal of the well head may be had and that a double seal about the tubing is thus provided if it is desired to use the insert in lieu of the slips.

The bleeder line 55 or the line 86 may also be used for the purpose of injecting a lubricant around the wiper rings while the tubing is being passed therethrough. It has been found that an oil lubricant, plain or soapy water are very satisfactory for this purpose, and it is intended that a quantity of lubricant may be injected under pressure and the valves closed to retain the same in contact with the tubing so that the wiping rings will not be burned or scoured while removing the tubing.

It seems readily apparent that there are several combinations of structure disclosed in this application; that they may be used either in combination or in lieu of each other in order to maintain a complete seal upon the well while the tubing is being run in or withdrawn.

What I claim as new is:

1. An assembly for sealing well heads including a casing, a valve structure thereon, a closure head disposed above said valve, a string of tubing in said casing, an enlarged member on said tubing disposed between two of the tubing couplings at an elevation where the tubing is to be suspended and adapted to receive a coupling to suspend the tubing, and a set of retractable dogs carried by said casing and adapted to receive said enlarged member to suspend said string of tubing.

2. An assembly for sealing well heads including a casing, a valve structure thereon, a closure head disposed above said valve, a string of tubing in said casing, an enlarged member on said tubing disposed between two of the tubing cou-

- plings at an elevation where the tubing is to be suspended, and a set of dogs carried by said casing and adapted to receive said enlarged member to suspend said string of tubing by receiving in said enlarged member the tubing coupling next above. 5
3. A hanger construction for the tubing in well casings including a hanger collar slidable on the well tubing and adapted to pass tubing collars, 10 means on the casing to support said hanger, and means on the tubing to engage said hanger. 15
4. A hanger construction for the tubing in well casings including a hanger collar slidable on the well tubing and adapted to pass standard tubing couplings, means on the casing to support said hanger, and means on the tubing to engage said hanger, said means including an enlarged member above and below said collar on the tubing string to seat and unseat said collar. 20
5. In combination with a well casing head assembly, means to hang a string of tubing in the well casing, a means to seal about the tubing including a housing, alternately spaced support and sealing rings in said housing, and oppositely concaved adjacently disposed faces on said rings forming a fluid trap whereby a greater pressure area to provide a seal is obtained, and means to bleed said trap. 25
6. A hanger construction for tubing in well casings including a connection on the casing, blocks carried by said connection, an enlarged member on the tubing to seat on said blocks, said blocks and said member being formed to pass standard couplings on said tubing, and an enlarged coupling to seat in and suspend the tubing from said member. 30
7. An assembly for sealing well heads, a casing, a pipe in said casing, a head supported on said casing, a seat in said head with an internal bore 40 large enough to pass regular collars of said pipe but adapted to receive an enlarged member of said tubing to form a fluid tight joint, means detachably mounted on said head to resiliently seal about said pipe and collar, said sealing means including rings of resilient material for successively reducing the well pressure, means for bleeding off reduced pressure, additional resilient sealing means above said bleed off, and means above said sealing means to support said pipe, said means including a downwardly tapered bowl. 45
8. An assembly for sealing a well head including a casing, a pipe therein, a supporting fitting on said casing, a valve on said fitting, sealing means around said pipe above said valve, a bushing on said pipe adapted to be supported by said supporting fitting, said bushing adapted to pass the standard collars on said pipe, but to support an enlarged member therein, said bushing having external fluid passageways, and said pipe being removable from said enlarged member to 55 permit closure of said valve. 60
9. In combination with a well head, a casing, a support fitting thereon, a valve on said fitting, a pipe in said casing, a bushing adapted to be supported by said support fitting, said bushing also adapted to pass the standard collars on said pipe and to support in sealing engagement an enlarged member on said pipe, said well head adapted to seal about an extension of said pipe and permit 65 disconnection from said enlarged member to permit the closure of said valve. 70
10. A closure for well heads including a casing, a pipe therein, a head on said casing, circular rings of resilient sealing material in said head, said rings being concaved and downwardly tapered to form a thick lip at the inner section 5 on the high pressure side and on the low pressure side being flat and adapted to be supported by a metallic ring when subjected to pressure, said ring being of just sufficient diameter to freely permit passage of collars on said pipe so 10 that the entire ring with the exception of the lip is supported against upward movement. 15
11. A closure for well heads including a casing, a pipe therein, a head on said casing, circular rings of resilient material in said head, said 15 rings being downwardly tapered at the inner section on the high pressure side, the outer section of said rings being adapted for clinching engagement with holding rings in said head, and the middle section of said rings being substantially 20 perpendicular to the axis of said pipe, said perpendicular section being greater in width on the low pressure side than on the high pressure side. 25
12. A closure for well heads including a casing, a pipe therein, a head on said casing, circular rings of resilient material in said head, a downwardly flaring projecting lip on each ring, circular rings of metal between said resilient rings adapted to support said resilient rings on the low pressure side, and said metallic rings being of 30 just sufficient inside diameter to freely pass the collars on said pipe, said resilient rings having the thickened lip to contact the pipe to form a seal and of a size which will not flex around the metal rings. 35
13. A hanger construction for tubing in well casings including a connection on the casing, blocks carried by said connection, an enlarged member carried by the tubing to seat on said blocks, enlarged couplings on said tubing above 40 and below said member, and means on said member to receive the upper enlarged tubing coupling to suspend the tubing string from said member. 45
14. A well head construction including a tubing and casing, means thereon to support the tubing in said casing, closure means for the casing above said means, and additional means to seal about the tubing above said casing closure means, said first means being so constructed as to provide 50 movable means which are adapted to leave a full open casing. 55
15. In a well head assembly a well casing and pipe therein, means to seal about said pipe including a resilient member about the pipe, an undercut downwardly extending lip on said member to seal with said pipe, and additional sealing means independent of said member to also seal about and support said pipe. 60
16. An assembly for sealing a well head including a casing, a pipe therein, a supporting fitting on said casing, a valve on said fitting, sealing means around said pipe above said valve, a bushing on said pipe adapted to be supported by said supporting fitting, said bushing having external fluid passageways, and said pipe being removable from said fitting to permit closure of said valve. 65

CERTIFICATE OF CORRECTION.

Patent No. 2,082,107.

June 1, 1937.

JAMES H. HOWARD.

It is hereby certified that the name of the assignee in the above numbered patent was erroneously written and printed as "J. M. McEvoy & Company" whereas said name should have been written and printed as J. H. McEvoy & Company, a corporation; as shown by the records of assignments in this office; and that the said Letters Patent should be read with this correction therein that the same may conform to the record of the case in the Patent Office.

Signed and sealed this 24th day of August, A. D. 1937.

Leslie Frazer

(Seal)

Acting Commissioner of Patents.
